UNITED STATES PATENT OFFICE.

MELVILLE A. CLARK, OF SYRACUSE, NEW YORK.

HARP.

1,105,879.

Specification of Letters Patent.

Patented Aug. 4, 1914.

Application filed November 28, 1911. Serial No. 682,858.

To all whom it may concern:

Be it known that I, MELVILLE A. CLARK, of Syracuse, in the county of Onondaga, in the State of New York, have invented new and useful Improvements in Harps, of which the following, taken in connection with the accompanying drawings, is a full, clear, and exact description.

This invention relates to certain improvements in harps of the class set forth in my Patent No. 1,005,157 October 10, 1911 except that the bridge pins are omitted and the strings are normally drawn in straight lines from the tuning pins to their points of attachment to the sounding board.

The main object is to increase the vibratory length of the strings without actually lengthening them or increasing the size of the string-supporting frame which is accomplished by omitting the usual bridge pins and allowing each string to vibrate from its tuning pin to its point of connection with the sounding board. In other words I have sought to produce a comparatively small and easily portable harp with a volume and quality of tone equal to or exceeding that of similar instruments of much larger size.

Another object is to provide means for fretting the strings at will to change the pitch thereof.

Other objects and uses will be brought out in the following description.

In the drawings:—Figure 1 is a face view of a portion of the neck of a harp showing adjacent portions of the strings, tuning pins and fret keys. Fig. 2 is a top plan partly in section of the mechanism shown in Fig. 1. Fig. 3 is a transverse sectional view through the neck of the harp showing one of the tuning pins and adjacent portion of its string and also showing one of the fret keys and sleeve in which it is journaled, the sleeve being shown in section. Figs. 4 and 5 are enlarged transverse sectional views through one of the fret keys and sleeve taken respectively on lines 4—4 and 5—5, Fig. 3, the fret key being shown in its normal position in Fig. 4 and in position for withdrawal from the sleeve in Fig. 5. Fig. 6 is an enlarged end view of the fret key and sleeve together with the adjacent portion of the string and retracting spring for the fret key, the latter being shown in its fretting position. Fig. 7 is a perspective view of the detached fret key.

Fig. 8 is an enlarged perspective view of one of the detached sleeves.

In order that my invention may be clearly understood, I have shown the neck as —A— of a harp having the usual hollow standard, sounding board and pillar, not shown. The neck —A— is provided near its upper longitudinal edge with a row of apertures —1— for receiving a corresponding number of tapering tuning pins —2— which are tightly fitted therein and extend some distance beyond opposite faces thereof, said neck being also provided near its lower longitudinal edge with a series of sockets —3— opening from one side thereof nearest the strings for receiving a corresponding number of metal sleeves or journal bearings —4—, one for each tuning pin and preferably located substantially midway between the strings as —b—.

A series of fret keys —5— are provided with reduced cylindrical ends —6— journaled in the sleeves —4— and are provided with eccentric portions —7— at the outer ends of the sleeves to contact with and deflect the adjacent portions of the strings for changing the pitch thereof, as, for example, in sharping or raising the pitch a half tone.

Each of the sleeves —4— may be driven or otherwise forced with a tight fit into its aperture —3— and is provided with one or more fins —10— on the periphery thereof for holding it against turning or endwise displacement, said sleeve being also divided through one side to form a lengthwise slot —11— for receiving a fin —12— on the inner end of the reduced portion —6— of the fret —5— to permit said key to be inserted into and withdrawn from its operative position.

The inner end of the reduced portion —6— upon which the fin —12— is formed extends some distance beyond the inner end of the sleeve when the fret key is adjusted for use and serves to hold said key against accidental withdrawal from the sleeve except when the fin is carefully registered with the slot —11—, the relative positions of the slot and fin being such as to prevent the withdrawal of the key when the latter is in its normal position of rest and also when it is adjusted to its fretting position so that in order to remove or insert the key, it must be adjusted to an intermediate position in registration with the slot —11—.

A portion of one side of one end of the

5 **DISCLOSURE OF INVENTION**
 sleeve is cut away to form 'stop shoulders' —13— and —13'— as best seen in Figs. 4; 6 and 8 for engaging opposite sides of the cam or eccentric —7— and thereby limiting the 10 rocking movement of the key to slightly more than a quarter turn. For example, the shoulder —13— limits the return movement of the key from its fretting position to a substantially vertical position midway between the strings, while the shoulder —13'— permits the cam to be moved slightly above a horizontal plane so that the pressure of the string against the edge of the cam will tend to hold it against the stop shoulder —13'— against the action of a retracting spring —14— which serves to hold the key in its normal or inoperative position against vibration or accidental contact with the string. This spring is preferably coiled 20 around the outer end of the sleeve and has one end secured thereto and its other end bearing against the side of the cam adjacent the string with which it is adapted to engage, said spring being comparatively light 25 and of just sufficient tension to return and hold the fret key in its normal position.

What I claim is:

1. A harp having rotarily adjustable fret keys and retracting springs therefor.
2. A harp having rotarily adjustable fret keys, non-rotatable sleeves therefor and spring connections between the sleeves and their fret keys for returning said fret keys out of contact with the strings.
3. A harp having rotarily adjustable fret keys, stops for limiting the movement of the fret keys in one direction and springs for yieldingly holding their respective keys against said stops.
4. A harp having rotarily adjustable fret keys, separate sets of stops for limiting the movement of their respective keys in reverse directions, and retracting springs for said keys normally holding them out of engagement with the strings.
5. A harp having rotarily adjustable fret keys, separate non-rotatable bearing sleeves for the keys, stops on the bearing sleeves for limiting the turning movement of the corresponding keys, and separate retracting springs for said keys.

PRINCIPAL CLAIM

6. In combination with a neck of a harp, separate bearing sleeves secured therein against rotation, and rotarily adjustable fret keys journaled in said sleeves. 55

7. In combination with the neck of a harp, separate metal bearing sleeves secured therein against rotation, fret keys rotarily adjustable in said sleeves, and separate retracting springs for the fret keys. 60

8. A harp having rotarily adjustable fret keys, separate bearings therefor, said keys having means coacting with portions of their respective sleeves to prevent accidental withdrawal of the keys from said sleeves. 65

9. A harp having rotarily adjustable fret keys and non-rotatable sleeve bearings therefor, fins on the keys coacting with portions of their respective sleeves to prevent accidental withdrawal of the keys when adjusted 70 rotarily to a predetermined position.

10. A harp having rotarily adjustable fret keys and bearings therefor slotted lengthwise through one side, said keys being provided with fins movable into registration 75 with their respective slots to permit their withdrawal from the sleeves, said fins coacting with portions of the sleeves to hold the keys against withdrawal when the fins are not registered with the slots. 80

11. In combination with the neck of a harp, separate bearing sleeves secured in said neck against rotation and provided with limiting stops, and fret keys adjustable rotarily in their respective sleeves and having 85 portions thereof coacting with said stops to limit their turning movement.

12. In combination with the neck of a harp, separate bearing sleeves secured in said neck against rotation and provided with limiting stops, fret keys adjustable rotarily in said sleeves and having portions thereof coacting with the stops to limit their turning movement, and separate retracting springs for the keys. 90 95

In witness whereof I have hereunto set my hand on this 20th day of November 1911.

MELVILLE A. CLARK.
